UNITED STATES PATENT OFFICE.

JOSEPH C. STEINER, OF WAUWATOSA, AND MIKE PETE MIKAS, OF MILWAUKEE,
WISCONSIN.

BRUSH.

Application filed October 20, 1927. Serial No. 227,512.

This invention relates to improvements in brushes.

It is one of the objects of this invention to provide an improved brush which will facilitate the cleaning of garments.

It is a further object of this invention to provide a device for steaming and brushing clothes in one operation.

It is a further object of this invention to provide a brush in which the flow of steam may be readily controlled from the handle of the device.

It is a further object of this invention to provide a brush having a brush holding plate with perforations therein, through which a fluid such as steam may be discharged at will, to circulate among the bristles of the brush.

It is a further object of this invention to provide a brush which is simple in construction and operation, and which is well adapted for the purpose described.

With the above and other objects in view, the invention consists of the improved brush and all its parts and combinations as set forth in the claims and all equivalents thereof.

In the accompanying drawing, in which the same reference characters designate the same parts in all of the views:

Fig. 1 is a longitudinal vertical section of the improved steam brush;

Fig. 2 is a transverse sectional view thereof taken on line 2—2 of Fig. 1, and

Fig. 3 is an end view thereof, parts being broken away.

Referring to the drawing, the numeral 5 designates a casing, to each end of which, secured by screws 6, is an upwardly extending handle holding bracket 7. Connecting the upper ends of the handle holding brackets, and extending through a bore in a handle 8, is a horizontal rod 9, having one end threaded, as at 10, to hold the rod in place.

The casing 5 is in the shape of an inverted cup, within which there is a convex partition plate 11 formed with a central boss 12. Between the upper portion of the casing and the partition plate is an upper steam chamber 13. Below the partition plate, and separated from it by a lower steam chamber 14, is a plate 15, preferably of copper. Below the copper plate and adjacent thereto,

is a strip of cloth or insulating material 16. A bristle holding plate 17, preferably of aluminum, in which a plurality of bristles 18 are held to form a surface engaging member or brush, is positioned below the insulating material 16. Extending through the bristle holding plate, the insulating material, and the copper plate, are a plurality of vertical perforations 19. These perforations are for the purpose of allowing the steam or other fluid in the lower chamber 14 to pass through the plates and circulate among the bristles 18. The bristle holding plate, the insulating material, and the copper plate are secured to the partition plate 11 by screws 20. The upper portion of the casing 5 is formed with a depressed portion 21 on which there is a downwardly extending boss 22 meeting the boss 12 of the partition plate. Within the depressed portion, and secured to the casing 5 by screws 23, is a valve plate 24. A steam passageway 25 extends through the depressed portion of the base member 5 and into the valve plate to an enlarged valve chamber 26. At the point where the passageway meets the valve chamber, the valve seat 27 is formed. Slidably positioned within the plate 24 is a valve needle 28. The partition plate 11 is connected to the upper portion of the base member by a bored screw 29 extending through the boss 12 and into the boss 22.

Extending downwardly from the valve chamber 26 and joining the bore of the screw 29, is a steam outlet 30. When the valve is opened, steam which is admitted into the outlet 30 flows into the lower chamber 14 and out through the perforations 19. One end of the valve plate 24 has a threaded projection 31 upon which is a knurled nut 32. Adjacent the knurled nut and on the outer end of the valve needle is a notched member 33 having a lug 34 on its outer end. A spring 35 having one end surrounding the lug 34 and its other end surrounding a lug 36 on the handle holding bracket 7, holds the valve stem yieldingly in a closed position. A lever 37, pivoted to a projection 38 on the handle holding bracket 7, and engaging the notched member 33 with its lower end, is arranged to open or close the valve.

A steam inlet tube 39 connected to a perforation 40 in the casing 5 admits steam into

the upper chamber 13. A tube 41 connected to a perforation 42 is provided to admit compressed air to dry the garment.

The operation of the device is as follows:

- 5 The upper chamber 13 is filled with steam which has been admitted under pressure from the inlet tube 39. The user grasps the handle 8, and by operation of the conveniently located lever 37, opens the valve.
- 10 This causes the steam from the upper chamber to pass into the valve chamber 26 and then through the outlet 30 into the lower chamber 14. The steam in the lower chamber immediately passes through the perforations 19 and circulates among the bristles 18. The action of the steam in combination with the brush will serve to effectively remove dirt and other foreign matter from garments. The steam may be shut off whenever it is desired by the operation of the lever 37. If a constant flow of steam is necessary, the knurled nut 32 may be loosened. This will bear against the notched member 33 and will thus open the valve and hold it in that position as long as it is desired, without making it necessary to hold the lever 37 down. When the garment has been well steamed the steam supply may be shut off and compressed air admitted through
- 25 the opening 41. This will tend to dry the garment which necessarily has absorbed considerable moisture from the steam.
- 30 A third opening 43 is provided as an outlet for water which has accumulated due to condensation of the steam within the chamber.
- 35 From the foregoing description, it may be seen that the improved steam brush is simple in construction and operation, and is well adapted for the purpose described.

What we claim as our invention is:

- 40 1. A cleaning device comprising a surface engaging member, an upwardly extending support connected at each end of said surface engaging member, a handle mounted between said supports, means for discharging a fluid below said surface engaging member, a valve seat in connection with said means, a valve needle in connection with said seat, a notched member on the outer end of said valve needle, a spring engaging said notched member, and a lever pivoted to one of the upwardly extending supports and having its lower end engaging the notched member and its upper end adjacent the handle.
- 45 2. A cleaning device comprising a casing having a fluid inlet, a plate mounted on the upper surface of said casing, a partition within said casing dividing the latter into
- 50 an upper and lower chamber, said partition being connected at an intermediate point with the upper surface of the casing, said connecting portion, plate, and casing having communicating ducts therein connecting the upper and lower chambers, means in connection with the duct in the plate for controlling the passage of fluid therethrough, and a surface engaging member below the lower chamber having perforations therein for discharging the fluid.
- 55 3. A cleaning device comprising a casing having a fluid inlet and having a depressed portion in its upper side with a bore therein, a partition within said casing dividing the latter into an upper and lower chamber, said partition being connected at an intermediate point with the depressed portion of the casing, and said connecting portion having a duct extending therethrough, a plate in the depressed portion of the casing, said plate having a duct therein extending from the bore in the depressed portion of the casing to the duct in the connection between the partition and the depressed portion of the casing, means in connection with said duct in the plate for controlling the passage of fluid therethrough, and a surface engaging member below the lower chamber having perforations therein for discharging the fluid.
- 60 4. A cleaning device comprising a casing having a fluid inlet and having a depressed portion in its upper side with a bore therein, a partition within said casing dividing the latter into an upper and lower chamber, said partition being connected at an intermediate point with the depressed portion of the casing, and said connecting portion having a duct extending therethrough, a plate in the depressed portion of the casing, said plate having a duct therein extending from the bore in the depressed portion of the casing to the duct in the connection between the partition and the depressed portion of the casing, a valve chamber in the plate in connection with said duct, a valve needle in connection with said valve chamber, a notched member on the outer end of said valve needle, a spring engaging said notched member, a lever engaging the notched member to open or close the valve, means on the valve plate for maintaining the valve in an open position, and a surface engaging member below the lower chamber having perforations therein for discharging the fluid.

In testimony whereof, we affix our signatures.

JOSEPH C. STEINER.
MIKE PETE MIKAS.
